(57) **CLAIM**

The ornamental design for a slatwall section, as shown and described.

DESCRIPTION

FIG. 1 is a front perspective view of a slatwall section showing my new design;

FIG. 2 is front elevational view of FIG. 1;

FIG. 3 is a rear elevational view of FIG. 1;

FIG. 4 is a top edge view of FIG. 1;

FIG. 5 is a bottom edge view of FIG. 1;

FIG. 6 is a left edge view of FIG. 1; and,

FIG. 7 is an enlarge view of a section taken from FIG. 6. Portions shown in phantom lines do not form a part of the claimed design.

1 Claim, 3 Drawing Sheets

FIG. 1

FIG. 2

FIG. 3
